[57] CLAIM

The ornamental design for a card file, as shown and described.

DESCRIPTION

FIG. 1 is a top plan view of a card file showing my new design;

FIG. 2 is a front elevational view, the rear elevational view being a mirror image;

FIG. 3 is a right side elevational view, the left side elevational view being a mirror image;

FIG. 4 is an upper, front perspective view with the slider in a opening position; and,

FIG. 5 is an upper, front perspective view with the slider in a tightening position.

The cards depicted by means of broken lines being shown for illustrative purpose only and forming no part of the claimed design.
